VAPORPROOF BUILDING CONSTRUCTION

Grant S. Willey, Chicago, Ill., assignor to United States Gypsum Company, Chicago, Ill., a corporation of Illinois

Application October 4, 1945, Serial No. 620,216

7 Claims. (Cl. 72—124)

1

The present invention relates to a vapor-proof building construction.

More particularly the invention concerns a type of vapor-proof building construction comprising a foraminous plaster-support that is affixed to supporting structures such as studs and the like, and is provided with openings through which thereto applied plaster may pass for the formation of plaster keys behind the support, but which structure is provided with means to prevent the transfer of humidity from the space defined by the plaster wall into the hollow wall space behind it.

With the advent of air-conditioning in modern homes and also the use of insulation, new problems have arisen which have tested the ingenuity of building constructors. One of these difficulties lies in the fact that there exists a very abrupt temperature gradient between the exterior of a house and the interior surface of the walls of the rooms thereof; this being occasioned by the fact that insulation is frequently used, or at least the air space between the wall of the room and the outside wall of the house is depended upon to guard against both loss of heat in the wintertime and the absorption of heat by the rooms as a result of the high outside temperatures.

The difficulty in the winter is accentuated by the fact that it has now become quite common practice to humidify the rooms of a house, this being usually accomplished by humidifying devices associated with the heating system.

It is a well known fact that the ordinary plaster wall is pervious to moisture in the form of water vapor. Moreover, the temperature on the inside of a room is generally kept on the order of between 70 and 75° F., while the outside temperature surrounding the house may be as low as 15 to 20° below zero F. Naturally there will exist in the space between the outer wall of the house and the wall of the room a temperature gradient between these two extremes of temperature. Inasmuch as cold air is capable of holding a great deal less moisture, it will follow that any moisture which penetrates through the plaster walls will be condensed within the space between the outer walls of the house and the walls of the room either in the form of water or, if the temperature is low enough, in the form of ice. When ice is formed, the conditions become greatly aggravated, as a considerable thickness of ice can build up which, as the temperature rises, will melt and therefore will turn into water, which not only will tend to run down the interior of the walls and possi-

2

bly appear on the ceilings of the floor below, but also will tend to rot the timbers, studs, and beams of the house.

The most radical cure for this condition is to eliminate the humidification. This, however, makes the interior of the house very dry, and the average householder who is not aware of the formation of the ice or moisture in his walls usually tries to keep his home at about 30 per cent relative humidity. It is therefore advisable to prevent the transmission of moisture into the space between the walls by the use of a vapor-impermeable barrier, and also thoroughly to ventilate the space beyond the vapor-proof barrier, so that if any moisture should penetrate, nevertheless it would be carried off. This can readily be done in attics and mansards, but is not so easy in the vertical walls of a building. Therefore, the best solution is simply to prevent access of the moisture in the first place.

It has already been proposed to employ plasterboard of the unperforated variety, the reverse side of which, that is to say, the side toward the outer wall of the building, being provided with an impervious sheet of either asphalted or similarly waterproofed paper and/or a sheet of metal foil, as for instance aluminum foil. The aluminum foil is particularly advantageous in that it not only provides a thorough vapor-proof barrier, but also by reason of its heat-reflecting properties prevents the entry into the room of radiant heat, and also by reason of its low heat-emissivity prevents the radiation of heat from the room when the room is at a higher temperature than that of the circumambient atmosphere.

Such plasterboard, however, while excellent for producing walls, does not furnish quite as good a plaster key as is desired. Moreover, in some parts of the United States the building codes require the use of plaster-supports having means thereon or therein for the formation of plaster keys. When plasterboard is used which does not have a vapor barrier on one side, this is usually accomplished by perforating the board, and many patents have been taken out on various types of perforated plasterboard, as for example perforated gypsum plasterboard as exemplified by Roos Patent No. 1,938,354.

It will be self-evident, however, that merely to cover the imperforate portions of the reverse side of the plasterboard with metal foil or other vapor barrier would not solve the problem above outlined, because the plaster which extends through the perforations and forms clinching heads (so-called "keys") would still permit the

passage of moisture through the said keys, and hence into the space between the outer and inner walls of the building.

Applicant has succeeded in solving this problem by providing a foraminous plaster support which may, for example, be exemplified by a perforated gypsum plasterboard, wood-fiber board, asbestos insulation board, or similar plaster-accepting base, this being provided with a vapor-impermeable backing membrane coextensive therewith, there also being provided extensible portions either associated with said membrane by attachment thereto or integrally formed therewith, these extensible portions permitting the intrusion thereinto of plaster keys which extend through the openings in the plaster support but which do not impair the continuity and vapor-stopping characteristics of the backing membrane.

This may be accomplished in a number of specific ways all of which will be more completely hereinafter described in connection with a single sheet of drawings in which

Fig. 1 is a perspective view, partly broken away and partly in section, of a wall construction embodying one of the preferred ways of accomplishing the results intended to be accomplished by the present invention;

Fig. 2 is a cross section, on an enlarged scale, of the construction shown in Fig. 1, the view being taken along the lines 2—2 of Fig. 1;

Fig. 3 is a cross section of a portion of a plasterboard having a vapor-impermeable backing membrane and extensible portions thereon;

Fig. 4 is a rear view of the one type of construction showing a plasterboard having extensible pockets subtending each of the openings or perforations in the plasterboard;

Fig. 5 is a cross section along the line 5—5 of Fig. 4, indicating the general appearance of a finished construction showing the distortion of the plaster key receiving pockets of the type shown in Fig. 5;

Fig. 6 is a side elevational view of one of the pockets shown in Fig. 4;

Fig. 7 is a cross sectional view of a portion of a wall showing both the outer and inner walls, but in a modified form, showing two plaster boards, one perforate and the other imperforate, the vapor-proof barrier being applied to the imperforate board; and

Fig. 8 is a perspective view, partially in section, of still another modification, in which the impermeable membrane is in the form of a readily distortable, for example crinkly, material.

The vapor barrier which is provided may consist of a suitable vapor-impermeable material such for example as asphalt-saturated paper, paper or other fabric saturated or impregnated with an artificial resin preferably of a flexible type, as for example a vinyl resin or other elastomer; or a sheet of metal foil, for example, aluminum foil or tin foil, which may be used either alone or in the form of a metal foil-paper or fabric laminate. The pockets may be merely folded portions of this membrane or film, or they may be in the nature of a bellows having accordion plaited side walls. In other words, the exact nature of the material of which the membrane is made is subject to a wide choice and the invention is not limited, in its broadest sense, to any particular material, although a vapor-proof paper, a metal foil, or a metal foil-paper or fabric laminate are the three selected species

which illustrate the general principles of the present invention.

Referring to Figs. 1, 2 and 3, these show a construction in which a foraminous plaster-support, for instance a suitable plasterboard 10, which is provided with suitable openings or perforations 11 and the usual cover sheets 12 and 13, is also provided with a therewith coextensive backing sheet 14 which may for example be made of any of the materials hereinabove mentioned. This sheet while it may be, if desired, adhesively secured to the cover sheet 13 of the plasterboard, is provided with longitudinally extending pockets 15 which are so oriented that they will subtend an entire row of the openings 11 through which the plaster keys penetrate.

As can best be seen from Figs. 1 and 2, which show the completed construction, there exists in the order named, and counting from the interior 20 of the room, the plaster layer 16, the outer cover sheet 12 of the plasterboard, the core of the plasterboard, the inner cover sheet 13 of the plasterboard, the vapor-impermeable layer 14, and the pockets 15 formed therein. The plaster keys 17 protrude into the pockets 15 as can be clearly seen in Figs. 1 and 2. The plasterboards themselves are supported by studs 18, there being shown, for the sake of completeness, also the outer sheathing 19 and the thereto affixed clapboards 20.

In the particular construction shown in Fig. 1, the pockets 15 extend the full length of each of the boards, even at those points where there are no perforations. The board when sold to the consumer will have the appearance in cross section as shown in Fig. 3, so that it can readily be put up in bundles because when shipped the pockets 15 are practically crushed flat as shown in Fig. 3. When in use, however, the pockets are of course expanded as illustrated in Figs. 1 and 2. The pockets are crushed down flat against the studding in order effectively to seal the room from the wall-space behind the vapor barrier.

An alternative construction comprises applying a continuous sheet 14' to the unperforated areas 45 on the back of the board, and then to apply at such points as to surround the subtending openings 11, a suitable telescoping type of pocket 25 (see Figs. 4, 5 and 6). These pockets are adhesively secured to the sheet 14' and when not in use are of course crushed flat against the back of the board, which is possible by reason of the accordion plait 26 which characterize this type of pocket.

The means for securing the pockets 25 to the 55 impermeable sheet may be some suitable water resistant adhesive, as for example asphalt and the like. When in use, the keys 17 will cause the expansion of the plait 26 and the general appearance of the pockets will be about as illustrated in Fig. 5. It is, however, within the contemplation of the invention to form these individual pockets 25 integrally with the sheet.

In Fig. 8 there is illustrated another manner 60 of accomplishing the purposes of the present invention in which case the sheet 14 is made of a crinkled fabric or metal foil, or fabric or paper-metal foil laminate. This will be adhesively secured in certain areas only to the plasterboard cover sheet 13 so that the sheet will still be sufficiently extensible at those points which subtend the openings 10, so that when the plaster keys 17 are formed, they will push back the crinkled material to form the bulges or pockets 35 which are shown both in perspective as well as in cross section in Fig. 8. This construction is particu-

larly advantageous in that it is inexpensive and also is comparatively strong, as there is not much danger of tearing the pockets open during shipping of the boards and the erection of the structure.

By the hereinafter used term "extensible portions associated with said membrane" it is intended to cover both the type of elongated pockets shown in Figs. 1, 2 and 3, the accordion plaited pockets 25 shown in Figs. 4 and 5, and the self-formed pockets 35 formed in the crinkled sheet shown in Fig. 8.

There is still another manner of effecting the purpose of the present invention, this being illustrated in Fig. 7. In this case the plasterboard 10 provided with the outer cover sheet 12 and the back cover sheet 13 is spaced from a solid plasterboard 30 which itself has cover sheets 31 and 32, but which is also provided with a continuous vapor impermeable barrier 34. A suitable furring means 36, which for instance may be in the form of slats, serves to affix the plasterboards 30 and 10 to each other, thus leaving a space 37 therebetween into which the plaster keys 17 may extend. The space 37 bounded by the plasterboards 10 and 30 and the furring means or slats 36 thus serves as pockets for the reception of the plaster keys 17. It will be self-evident that the impervious sheet 34 might just as well be so oriented as to face toward the studs 18 and still accomplish the purpose of preventing access of moisture into the space between the outer sheathing 19 and the plasterboard 30.

While plasterboards have been shown as the preferred form of the present invention, it will be self-evident that the support could consist of a suitably perforated metal or other material, for instance it might be a type of plaster-support consisting entirely of comminuted wood fiber, or in fact any type of perforated board to which plaster will readily adhere. In other words, the presence of the gypsum core within the plasterboard is not a limiting feature, but the invention has been described in connection with the common type of plasterboard or wallboard because this is the preferred embodiment of the present invention.

Accordingly, and saving for himself such equivalents as will occur to those skilled in the art into which this invention falls, applicant claims:

1. A vapor-proof building element comprising a plaster support having a plurality of spaced plaster-receiving openings, and a substantially vapor-impermeable backing membrane secured in flatwise relationship to one surface of said support extending across said openings, said backing membrane being crinkled in those areas over said openings whereby to provide extensible plaster-receiving pockets when plaster is forced through said openings from the other surface of said support.

2. A vapor-proof building element comprising a wallboard having a plurality of spaced plaster-receiving openings therein, and a substantially vapor-impermeable backing membrane adhesively secured in flatwise relationship to one surface of said wallboard extending across said openings, said backing membrane being crinkled over the openings thus providing extensible plaster-receiving pockets when plaster is forced through said openings from the other surface of said wallboard.

3. A vapor-proof building element comprising a plaster support having a plurality of spaced openings, and a substantially vapor-impermeable backing membrane secured in flatwise relation-

ship to one surface of said support and having portions extending over the openings and extensible outwardly therefrom, said portions each formed on opposite sides with a freely folded overlap of the membrane extending from parts of the membrane secured to the support on opposite sides of each opening, said portions being extensible to provide pockets for mortar forced through said openings from the opposite surface of the support.

4. A vapor-proof building element comprising a wallboard having a plurality of spaced plaster-receiving openings, and a substantially vapor-impermeable backing membrane secured in flatwise relationship to one surface of said wallboard and having portions extending over the openings and extensible outwardly therefrom, said portions each formed on opposite sides with a freely folded overlap of the membrane extending from parts of the membrane secured to the support on opposite sides of each opening, said portions being extensible to provide pockets for mortar forced through said openings from the opposite surface of the wallboard.

5. A vapor-proof building element comprising a plaster support having a plurality of spaced openings extending therethrough and arranged in spaced rows, and a substantially vapor-impermeable backing membrane secured in flatwise relationship to one surface of said support between said rows but unsecured in the areas along said rows and having portions extending over the openings and extensible outwardly therefrom, said portions each formed on opposite sides with a freely folded overlap of the membrane extending from parts of the membrane secured to the support on opposite sides of each opening, said portions being extensible to provide pockets for mortar forced through said openings from the opposite surface of the support.

6. A vapor-proof building element comprising a wallboard having a plurality of spaced plaster-receiving openings extending therethrough and arranged in substantially parallel spaced rows, and a substantially vapor-permeable backing membrane adhesively secured in flatwise relationship to one surface of said support between said rows but unsecured in the areas along said rows and having portions extending over the openings and extensible outwardly therefrom, said portions each formed on opposite sides with a freely folded overlap of the membrane extending from parts of the membrane secured to the support on opposite sides of each opening, said portions being extensible to provide pockets for mortar forced through said openings from the opposite surface of the wallboard.

7. A vapor-proof building element comprising a wallboard, a substantially vapor-impermeable backing membrane secured in flatwise relationship to one surface of said wallboard, said element having a plurality of spaced plaster-receiving apertures extending therethrough and through said membrane, and a plurality of flat plaited and extensible substantially vapor-impermeable pockets adhesively secured to said backing membrane in the areas thereof encompassing said openings and extending with their open ends thereacross whereby to provide extensible pockets for mortar forced through said openings from the opposite surface of said wallboard.
